UNITED STATES PATENT OFFICE.

ALBERT G. ELVIN, OF EAST ORANGE, NEW JERSEY.

FLUID-PRESSURE MOTOR FOR FIRE-BOX DOORS.

1,030,234.

Specification of Letters Patent. Patented June 18, 1912.

Original application filed February 5, 1907, Serial No. 355,877. Divided and this application filed September 28, 1909. Serial No. 519,998.

To all whom it may concern:

Be it known that I, ALBERT G. ELVIN, formerly of Franklin, in the county of Venango and State of Pennsylvania, but now 5 of East Orange, in the county of Essex and State of New Jersey, have invented a certain new and useful Improvement in Fluid-Pressure Motors for Fire-Box Doors, of which improvement the following is a specification.

My invention relates to fluid pressure actuated appliances for opening and closing the doors of fireboxes or furnaces, and is more particularly designed for use in connection with the locomotive firebox door mechanism set forth in an application for Letters Patent filed by me February 5, 1907, Ser. No. 355,877, of which application this is a division. It is not, however, limited 20 in application to said mechanism or to fire doors of any specific form or location.

The object of my invention is to provide an appliance for actuating fire doors by fluid pressure, which shall be of simple and 25 compact construction and reliable in operation, of ready applicability under limitations of space, and free from liability to derangement in operation.

The improvement claimed is hereinafter 30 fully set forth.

In the accompanying drawings: Figure 1 is a front view, partly in elevation and partly in section, of a firebox door appliance, illustrating an application of my invention; Fig. 2, a vertical section, on an enlarged scale, through the lower portion of the cylinder and its lower head, showing the operating valve as unseated for the supply of fluid to the piston; Fig. 3, a similar view, 35 showing the operating valve as seated for the exhaust of fluid from the piston; Fig. 4, a horizontal section through the cylinder and piston; and, Fig. 5, a vertical section through the lower portion of the cylinder 40 and its lower head, taken at right angles to Figs. 2 and 3.

My invention is herein exemplified as in connection with the fire door appliance of my application Ser. No. 355,877 aforesaid, 50 the same (which is not claimed herein) comprehending two door sections, 9, 9^a, which are fitted to slide toward and from each other in a door frame, 3, and to cover and uncover, as the case may be, a firing 55 opening in a fire box or furnace to which the

door frame is connected. The door sections are moved from and toward each other, to open and close, respectively, the firing opening, by means of levers, 12, 12^a, pivoted by pins or bolts, 13, to one side of the door frame, and carrying arms 14, 14^a, in which are formed curved slots, 15, engaging pins, 16, 16^a, formed or fixed centrally on the door sections, 9 and 9^a, respectively. Segment gears, 17, 17^a, are formed on the levers, 60 12, 12^a, on the sides of their pivots farther from the arms, 14, 14^a, and an operating handle, 18, is formed on the outer end of one of the arms, as the upper arm, 14, by the movement of which handle, through the 65 engagement of the curved slots, 15, with the pins, 16, 16^a, and the meshing of the teeth of the segment gears, 17, 17^a, the door sections may be manually simultaneously moved away from or toward each other, as 70 desired.

In the practice of my invention, as applied in connection with the door moving mechanism above described, a fluid pressure operating cylinder, 25, is bolted to the side 80 of the door frame, 3, which adjoins the segment gears, 17, 17^a, of the door section levers, and is closed at its upper and lower ends by heads, 26, 27. The cylinder, 25, is cut away on its side next the segment 85 gears, so as to allow them to project into it, and is fitted with a piston, 28, provided with suitable packing rings, 29, near its lower end. A longitudinal recess is formed in the piston 28, above its packing rings, and is 90 provided with a rack or plurality of teeth, 30, engaging the teeth of the segment gear, 17^a, of the lower door section. Upward movement is imparted to the piston by fluid pressure, which is preferably compressed 95 air, admitted to its lower end through a supply pipe, 31, and it is moved downwardly by a spring, 32, abutting on its upper end and on the upper head, 26, of the cylinder. It will be seen that the upward 100 and downward movement of the piston, will, respectively, through the segment gears and their connections, move the door sections apart or bring them together, as the case may be.

The supply and exhaust of motive fluid to and from the piston are effected by an operating valve, 33, which is of the lift or puppet type, and is fitted to move horizontally in a chamber, 34, in the lower cyl- 110

inder head, 27, which chamber, and the operating valve therein, are constantly exposed to the fluid pressure in the supply pipe, the operating valve being, consequently, normally held seated by said pressure. The operating valve is formed on or fixed to a cylindrical stem, 35, which projects outwardly through a corresponding bore in the lower cylinder head, in the direction of the door frame, and abuts against a downwardly projecting arm, 36, on a rock shaft, 37, journaled on said frame. The rock shaft, 37, carries a horizontally projecting arm, 38, which bears against one arm of a double armed lever, 39, journaled on a pin, 40, fixed in the door frame below the lower door section, and the opposite arm of said lever is connected to the inner arm of a double armed treadle lever, 41, journaled on the lower portion of the door frame. The outer arm of the treadle lever is bent downwardly to a level slightly above that of the deck or firing floor of the boiler, and carries a treadle, 42. By downward pressure of his foot upon the treadle, 42, the fireman can, through the lever system above described, unseat the operating valve, and, upon the release of such pressure, the valve will be reseated by the pressure from the supply pipe acting upon it in its chamber, 34.

A central supply passage, 43, is formed in the valve stem, 35, said passage communicating by radial ports, 44, with the valve chamber, 34, when the operating valve is unseated, and extending to radial ports, 45, leading into an annular peripheral groove or channel, 46, in the valve stem. As a mechanical equivalent for the central passage, 43, and radial ports, 44, a peripheral groove may be formed on the valve stem, in the plane of the ports, 44, and a lateral groove be formed on said stem connecting said peripheral groove with the groove or channel, 46, similarly to the central passage, 43, which is shown. In all positions of the operating valve and stem, the channel, 46, registers with a main supply and exhaust port, 47, leading through the lower head, 27, into the cylinder, 25, and, when the operating valve is seated, it also registers with a final exhaust port, 48, in the head, leading to the atmosphere. A preliminary exhaust passage, 49, is formed in the wall of the cylinder, said passage opening thereinto by a port, 50, located slightly below the level of the bottom of the piston, 28, when at the upper extremity of its traverse, and the lower end of the preliminary exhaust passage opens into the cylindrical bore in which the valve stem, 35, works, at such a point in the length thereof as to register with the channel, 46, of said stem, and, through said channel, with the final exhaust port, 48, when the operating valve is seated. The

area for traverse of fluid through the port, 47, is made less than that through the preliminary exhaust passage, and is varied, as desired, by a regulating valve, 51, formed on the end of an adjusting screw, 52, engaging a thread in the lower head, by the movement of which screw, the valve, 51, may be caused to close the port, 47, either entirely or to any desired degree.

In the operation of the motor, the fireman places his foot on the treadle, 42, and thereby depresses the outer end of the lever, 41, which, through the lever, 39, and rock shaft, 37, and its arms, transmits the applied pressure to the stem, 35, of the operating valve, 33, and unseats said valve. Operating fluid is thereby admitted to the cylinder, 25, below its piston, 28, through the ports, 44, passage, 43, ports, 45, peripheral channel, 46, and port, 47, the pressure of the fluid raising the piston to the limit of its upward traverse, in which, through the gearing and door levers, it moves the door sections away from one another the limit of their traverse, and fully opens or uncovers the firing opening. Said opening remains uncovered only so long as the pressure of the fireman's foot is maintained on the treadle, and, upon the release of this pressure, the operating valve is immediately seated by the pressure in its chamber, 34. The upper end port, 50, of the preliminary exhaust passage, 49, has previously been uncovered by the piston passing above it, and the lower end of said passage has, by the seating of the operating valve, been brought into communication with the channel, 46, and final exhaust port, 48. The port, 47, is also open to the channel, 46, and final exhaust port, 48. The operating fluid is therefore exhausted from the cylinder, and the piston is forced down by the spring, 32, bringing the door sections to their normal closed position in its downward movement. The preliminary exhaust being open before the piston commences its downward stroke, the larger portion of the operating fluid below the piston will be immediately released, thereby allowing the door sections to be quickly started in their closing movement, and as the port, 50, is closed by the piston in passing it, the remainder of the downward stroke of the piston and the resultant movement of the door sections will be made more slowly, owing to the comparatively restricted discharge opening through the port, 47, as regulated by the valve, 51. The piston will be thus, in a substantial degree, cushioned, so that while the door sections start to close quickly, they will come together easily and without shock.

The construction of the appliance is such as to involve comparatively few working parts, and these are of such character that they can be substantially made and are pro-

tected from liability to breakage and from damage by the access of dirt. The operation of the door sections is quick, simple, and easy, and the automatic closure of the door sections effects the substantial advantage of compelling single shovel firing, the advantage of which practice, in economizing fuel, perfecting combustion, and reducing firebox and flue repairs, has been universally recognized in railroad service.

I claim as my invention and desire to secure by Letters Patent:

1. The combination of a fluid pressure cylinder having a lateral opening and a closing head provided with supply, exhaust, and auxiliary exhaust ports, a piston working in said cylinder and having a rack on its side adjacent to said opening in position to engage a gear extending thereinto, an operating piston valve in the closing head of the cylinder controlling the supply, exhaust, and auxiliary exhaust of fluid to and from said cylinder, and a spring bearing on said piston and acting to effect its traverse in a direction opposite to that effected by the action of fluid pressure.

2. The combination of a fluid pressure cylinder having a lateral opening and a closing head provided with a direct supply and exhaust port, a piston working in said cylinder and having a rack on its side adjacent to said opening in position to engage a gear extending thereinto, an operating piston valve in the closing head which, when unseated, admits fluid pressure to the cylinder, and, when seated, exhausts fluid pressure therefrom, and which is continuously subject to fluid supply pressure, a lever for unseating the operating valve, and a spring bearing on the piston and acting to effect its traverse in a direction opposite to that effected by the action of fluid pressure.

3. The combination of a fluid pressure cylinder having a lateral opening and a closing head provided with a direct supply and exhaust port, a piston working in said cylinder and having a rack on its side adjacent to said opening in position to engage a gear extending thereinto, an operating piston valve in said closing head which, when unseated, admits fluid pressure to the cylinder, and, when seated, exhausts pressure therefrom, and which is continuously subject to fluid supply pressure, a lever system, one member of which contacts with the operating valve, means, for unseating the operating valve through the lever system, and a spring bearing on the piston and acting, when the operating valve is seated, to effect the traverse of the piston in a direction opposite to that effected by the action of fluid pressure.

4. The combination of a fluid pressure cylinder having a lateral opening and a closing head, a piston working in said cylinder

and having a rack on its side adjacent to said opening in position to engage a gear extending thereinto, a direct supply and exhaust port leading into the cylinder through the closing head, a preliminary exhaust port leading into the cylinder adjacent to the limit of traverse of the piston, a final exhaust port through the closing head, an operating piston valve controlling all of said ports and continuously subject to fluid supply pressure, and means for unseating the operating valve to admit fluid pressure to the cylinder and permitting it to be reseated by fluid pressure to exhaust fluid pressure from the cylinder.

5. The combination of a fluid pressure cylinder having a lateral opening and a closing head provided with a direct supply and exhaust port, a piston working in said cylinder and having a rack on its side adjacent to said opening in position to engage a gear extending thereinto, an automatically seating operating piston valve in said closing head and controlling the supply and exhaust of fluid to and from the piston through the supply and exhaust port, an adjustable valve in said head and port and interposed between the piston and valve, and means for unseating said operating valve.

6. The combination of a fluid pressure cylinder, a piston working therein, a head closing one end of the cylinder, and provided with an operating valve chamber and a cylindrical bore for an operating valve stem, a fluid supply pipe leading into the valve chamber, a main supply and exhaust port leading from the cylindrical bore into the end of the cylinder, a preliminary exhaust port leading from said bore into the cylinder in a plane adjacent to the limit of outward traverse of the piston, a final exhaust port leading from said bore to the atmosphere, an operating valve adapted to seat in the valve chamber at the inner end of said bore, a stem fixed to said valve and fitting in and passing through said bore, and having a peripheral groove or channel adapted to register with the ports aforesaid, a longitudinal passage in said stem having radial ports at its ends leading to the periphery of the stem adjacent to the valve and to the peripheral groove or channel respectively, and means for unseating the operating valve.

7. The combination of a fluid pressure cylinder, a piston working therein, a head closing one end of said cylinder and provided with an operating valve chamber, a cylindrical bore leading therefrom to the opposite side of the head, and an operating valve seat at the inner end of said bore, a main supply and exhaust port and a preliminary exhaust port, each leading from said bore into the cylinder, a final exhaust

4
port leading from said bore to the atmosphere, an operating valve adapted to close upon the valve seat, a stem fitting in and passing through said bore and having a peripheral groove or channel, a passage leading through said stem and having radial ports at its ends leading to said groove or channel and to the periphery of the stem, respectively, and a fluid supply pipe leading into the operating valve chamber.

8. The combination of a fluid pressure cylinder, a piston working therein, a head closing one end of said cylinder and provided with an operating valve chamber, a cylindrical bore leading therefrom to the opposite side of the head, and an operating valve seat at the inner end of said bore, a main supply and exhaust port and a pre-

liminary exhaust port, each leading from said bore into the cylinder, a final exhaust port leading from said bore to the atmosphere, a puppet valve in said valve chamber having a cylindrical stem in which are formed radial ports adjacent to the valve, a peripheral groove or channel between said ports and the opposite end of the valve stem, and a longitudinal passage connecting said radial ports and peripheral groove or channel, and means for operating the puppet valve to connect the radial ports with the main supply and cylinder.
